UNITED STATES PATENT OFFICE

WILBUR N. SQUIRES, OF JOPLIN, MISSOURI, ASSIGNOR TO HYDRAULIC DEEP WELL PUMP COMPANY, OF JOPLIN, MISSOURI, A CORPORATION OF MISSOURI

JACK MECHANISM

Application filed September 20, 1927. Serial No. 220,728.

My present invention relates to the art of pumping and more particularly it is applicable to the pumping of deep wells such as are encountered in oil fields though the invention is not to be restricted to that particular field. It has been proposed heretofore to raise the liquid from a well by reciprocating columns of liquid one of which is the discharge line such a system being disclosed 10 in my copending application, Serial No. 159,896, filed January 8, 1927.

The present invention is particularly directed to the pulsator or jack mechanism for reciprocating these columns of liquid to operate the pump in the well and to discharge 15 the quantity of oil brought up at each stroke of the pump.

One of the obstacles encountered in the pumping of oil wells by a pumping mechanism of this class is the evolution of gas. In many cases gas is evolved in the well and escapes up through the liquid standing in the casing. This gas which is drawn off at the casing head is not appreciably involved 20 in pumping of the oil from the well. The gas which I refer to is that which is evolved after the oil enters the pump or the pipe lines. In many cases the oil is saturated with gas and the agitation which is caused 25 by the pumping action releases the gas in the pump or in the reciprocating columns. Also the liquid usually comprises some light or volatile constituents which tend to volatilize under release of pressure.

25 The gas or vapor which thus or otherwise finds its way into the pump presents difficulty first in the pump cylinder and second in the reciprocating columns. Consider the case of a pump disposed in a deep well and 30 lifting oil against a head of the order of 1000# per sq. in. If the pumping cylinder should be filled with gas and a compression stroke is made obviously the gas must be compressed to a pressure sufficiently above 35 the head to lift the discharge check valve

otherwise the gas cannot be driven out of the cylinder and the pump would become air bound. This means that the compression ratio i. e. the ratio of displacement space to clearance space must be made great enough to insure expulsion of the gas against any head encountered by the pump. Preferably I provide a pump cylinder of relatively great length as compared to the bore to secure the desired compression ratio without being required to work to close dimensions on the intake and discharge valve passages and pockets. By this means I am able to pump out any gas which enters the pump cylinders.

The gas is then discharged into the discharge 40 line column where it presents a different problem. The discharge stroke of the pump cylinder is made by applying pressure to one side of the motor piston through the inner column of oil which remains substantially the same throughout the pumping operation. The suction stroke is made by applying pressure to the other side of the motor piston through the outer column of oil which serves also as the discharge line. While a certain 45 amount of gas may be evolved from the inner or high pressure column and provision must be made to get rid of it, the real problem is to get rid of the gas in the discharge or low pressure column. The gas in the discharge or 50 low pressure column tends to bubble up by gravity and it expands as it rises but this takes time and the pump may make many strokes before the particular body of gas can 55 rise from the bottom of the column. During 55 such strokes the pressure applied to said outer column compresses the gas in the column and due to the elasticity of the same the pressure of said column cannot be raised by the displacement of the jack piston as it could if 60 it were a solid liquid column.

My system is designed, first, to eliminate the gas from both columns as fast as it rises to the top of the column, and, second, the pump is designed to be operative to make the 65

strokes of the pump even if considerable gas is evolved in the oil being pumped.

In the preferred form of the pump the pump piston is single acting. The rod passes 5 through a packing which closes the one end of the pump cylinder. On the discharge stroke the pressure on the inner or high pressure column must be great enough to discharge the fluid contents of the pump cylinder 10 against the full head of the discharge. This may require very high pressure. At the same time the piston draws a vacuum in the closed end of the pump cylinder.

Then when the intake stroke is to be made 15 the pressure to be imposed upon the discharge or low pressure column need be only great enough to draw in a charge of liquid or gas from the well. Obviously, the suction prevailing back of the pump piston assists 20 this stroke. All the pressure required on this side is that which is needed to draw in a charge of liquid into the pump and to raise the opposite column.

Where considerable gas is contained in the 25 discharge column the elasticity of the column prevents the imposition of any great pressure upon the bottom of the motor piston. If the condition is extreme, I may modify the pump structure to employ a differential 30 motor piston presenting a greater area to the pressure in the discharge line than to the pressure in the inner line. Thus, by presenting differential areas to the two columns, the return stroke may be made without requiring 35 any pressure to be imposed on the discharge column than the actual head of the column.

I may, if desired, depend upon a difference 40 in area between the motor piston and the pump piston for making the suction stroke. This modified form of structure may be advantageously employed when the gas content is low and the discharge column is fairly continuous.

45 My present invention provides an automatic valve mechanism operable at each stroke of each column to release such gases as rise to the top of the column. Preferably this release occurs during the up stroke of 50 the column and during the initial part of the down stroke although obviously such release might be secured at any part of the stroke. While the operation of this gas release valve in one or both cylinders is automatic 55 while the machine is in operation, the length of time during which the valve is held open may be adjusted to meet the particular conditions of a particular well, the gases and any liquid released by this gas release 60 valve are conducted to a receiving tank which receives the liquid discharged from the system. Thus this gas discharge valve may be employed in eliminating not only gases but also to control the effective stroke of the actuating pistons in the head mechanism. 65

The use of this valve is advantageous to secure the proper displacement of the corresponding pulsator piston. The displacement required may vary depending upon the compressibility of the working medium and the 70 expansibility of the line under pressure. The compressibility of the working medium depends upon its composition and the amount of gas which it may contain. The expansibility of the power lines depends upon the pressure to which they are subjected. 75

I therefore, preferably construct the head mechanism with a length of stroke in excess of the actual displacement required to secure the full stroke of the motor mechanism of the pump in the well and by adjusting the point of closing of the gas release valve I make the displacement of the operating piston in the head mechanism correspond to the required displacement of the motor mechanism in the well. 80

In the operation of the head mechanism and the pump as I shall describe more in detail later, the jack mechanism and the pump may be out of time and an excess of liquid may be trapped under the operating piston so that operation of the jack mechanism would tend to place an excessive pressure on the connecting lines, the valves and the motor mechanism of the pump, particularly on starting up the 90 operation of a system of this character, and I therefore provide an automatic transfer or release between the reciprocating columns in each direction so that if, for example, the system should be started with the head mechanism out of phase with the pumping mechanism in the well, these two mechanisms would in a few strokes synchronize with each other 95 and proceed in an orderly fashion. 100

The manner in which I secure this synchronizing function is to employ a pair of conduits between the two columns and dispose in each of them a pressure release valve operating at a predetermined maximum, one in one direction between the columns and the other in the opposite direction between the columns. Obviously these valves may be disposed side by side in a single conduit. 105

In the operation of a system of this character it is necessary not only to maintain the columns intact as to liquid contents but also to permit the discharge of the excess of liquid which is discharged through the discharge line on the discharge stroke of the pump. For this purpose I provide an automatic let off valve for discharging the proper quantity of oil from the discharge column corresponding to the amount pumped on the discharge stroke. 115

120 My invention provides a jack mechanism including the above features and certain other features of novelty which will be apparent from the following detailed specification and drawings which form a part of my application. 125

In order to acquaint those skilled in the art with the manner of constructing and operating a device according to my invention, I shall describe in connection with the accompanying drawings a specific embodiment of the same.

Fig. 1 is a diagrammatic illustration of the jack mechanism and the pump embodying my invention;

10 Fig. 2 is a diagram of a modified form of pump adapted to be operated by the head mechanism;

15 Fig. 3 is a similar diagram of another form of pump for use in connection with my head mechanism;

Fig. 4 is a front elevational view of the jack mechanism;

Fig. 5 is a side view taken from the left of Fig. 4;

20 Fig. 6 is an enlarged view showing in elevation the adjustable trip mechanism for the gas release valve;

25 Fig. 7 is a longitudinal sectional view taken through the plunger and control mechanism for the gas release valve on the line 7—7 of Fig. 6;

Fig. 8 is a top plan view of the structure shown in Fig. 7;

30 Fig. 9 is a diagrammatic view of a detail, namely, the catch or detent for holding the gas release valve operating eccentric;

Fig. 10 is a diagrammatic plan view of the pipe connections between the jack and the well; and

35 Fig. 11 is a side elevational view of a modified detail, namely, the adjustable trip for releasing the catch shown in Fig. 9.

40 Referring first to Fig. 1 I provide a pump mechanism 1 disposed in the well, the casing of which is indicated at 2.

The pump 1 is suspended on the head of the casing through the medium of the outer or discharge pipe line 3 which leads by way of a conduit 4 to pulsator cylinder 5. The 45 pump is connected by an inner pipe 6 and conduit 7 to the other pulsator cylinder 8. These pipes and conduits are adapted to be filled with liquid constituting operating columns and the pipe 3 and conduit 4 constituting the discharge line of oil pumped from the well to a discharge line 9 which leads to a suitable receiver or tank into which the oil is pumped. The outer pipe 3 is adapted to receive the oil discharged from the pump 50 cylinder 10 through the discharge check valve 11 and the interior of pipe 3 communicates with the interior of the motor cylinder 12 below the motor piston 13, which motor piston is connected by a suitable rod 14 with the pump piston 15. The bottom of the pump cylinder 10 connects through an inlet check valve 16 and inlet passageway 17 with the oil in the well. The upper end of the pump cylinder 10 is closed off above the piston 15

55 through the medium of a packing and gland

18 so that the upper end of the cylinder 10 is closed against the entry or exit of the fluid to be pumped, provision being made as explained in my copending application, Serial No. 219,922, filed Sept. 16, 1927, for evacuating any fluid which may enter this close space by leakage or accident. The upper end of the motor cylinder above the piston 15 communicates with the inner pipe 6.

70 The cylinders 5 and 8 have therein suitable pistons or plungers 19 and 20 adapted to be reciprocated alternately to reciprocate the liquid columns contained in the pipes and conduits above referred to.

75 The mechanism for reciprocating these plungers 19 and 20 includes a shaft 21 having the crank discs 65 and 66 employing crank pins 24 and 25 connected by suitable connecting rods 26 and 27 to the plungers 19 and 20, respectively. It can now be seen by reference to Fig. 1 that as the plungers 19 and 20 are plunged up and down in opposite phase the liquid columns contained in the connections 3, 4, 6 and 7 will be synchronously reciprocated. Such reciprocation of the liquid 80 columns moves the motor piston 13 up and down to reciprocate the same in phase with the jack mechanism, thereby operating the pump piston 15 to draw in and expel successive charges of liquid from the well. Upon 85 each downward stroke of the pump piston 15 fluid is discharged from the pump cylinder past the check valve 10 against the head of the discharge column at that point and synchronously with said discharge a let-off valve 28 is operated as by means of a push rod 29 and cam 30 on the crank shaft 21 to permit the discharge of excess liquid out by way of the pipe 31, valve 28 and discharge connection 9 to the receiving tank.

90 100 The valve 28 closes at the same time that the plunger 19 begins to descend so that pressure imposed on the discharge column forces the piston 13 upwardly in the motor cylinder 12 and raising the pumping piston 15 to draw in a fresh charge of fluid from the well. At the same time that the motor piston 13 is raised the jack plunger 20 is also raised so that the liquid displaced by the motor piston 13 finds the proper space in the jack cylinder 8.

105 110 115 The lines 4 and 7 are connected by cross connections 32 and 33. These cross connections include the transfer valves 34 and 35, respectively. The transfer valves are spring loaded check valves, the spring loading being under suitable control to permit the valves to pop open in one direction when the pressure in the corresponding line exceeds the spring loading. The pressure in the opposite line simply forces the corresponding valve more tightly to its seat. Thus, for example, if the pressure in the line 7 should rise to an excessive value, higher than the spring loading in the valve 35, said valve would open and 120 125 130

permit liquid to be transferred from the line 7 to the line 4. In a similar manner if the pressure in the line 4 exceeds the spring loading of the valve 34 liquid will be transferred 5 from the line 4 to the line 7. Assume that the mechanism of the pump 1 is out of phase with the head or jack mechanism, as shown for instance in Fig. 1. The plunger 19 begins to descend and the plunger 20 begins to rise. 10 Since the plungers of the pump are out of time with the plungers of the jack mechanism the motor piston 13 will reach the end of its stroke before the jack plunger 19 has descended to the full limit of its stroke. The 15 liquid in the line 4 will thereupon have no escape and the pressure rising above the value of the spring loading of the valve 34 opens said valve and liquid moves through the cross connection 32 into the high pressure line 7. 20 The liquid which is thus transferred from one line to the other not only removes the excess which existed in the one line but supplies the deficiency which existed in the other to bring about phase synchronism between the 25 jack mechanism and the pump mechanism.

Obviously, if the two mechanisms were out of phase in the other direction, namely, if there were an excess of fluid in the pipe 7 liquid would be transferred from the pipe 7 30 to the pipe 4 through the opening of the loaded check valve 35.

With the above general explanation of the functions of the apparatus I shall now describe more in detail the structure of the jack 35 mechanism and its further functions, particularly in connection with the release of gas from the operating columns and the determination of the displacement of the jack pistons for correct operation of the pump.

The jack mechanism shown in the general views of Figs. 4 and 5 comprises two side frame members 40 and 41 provided at their lower ends with pedestals or feet 42 and 43 adapted to rest upon a suitable foundation. 40 These side frames are connected together by cross frame members 44 and 45 and the pedestals 42 and 43 are tied together by a cross brace 45. A portion of the discharge connection 31 is supported on the cross brace 46 and 45 the oil discharge valve 28 is contained in said portion of the pipe 31.

Pairs of arcuate brackets 47, 47 and 48, 48 are formed integrally with the side frames 40 and 41, respectively, and these support the 50 frames of the cylinders 5 and 8, respectively. These cylinders have integral flanges 49 and 50 resting upon the top of the brackets 47 and 48, respectively.

Suitable bolts such as 51 and 52 clamp the 55 flanges 49 and 50 to the supporting brackets. The upper ends of the cylinders 5 and 8 are closed by suitable packing and gland followers 53 and 54. The lower ends of the cylinders 5 and 8 are closed by heads 55 and 56. 60 Suitable street elbows 57 and 58 provide con-

nctions through the heads 55 and 56 to the pipe lines 4 and 7, respectively.

The cylinders 5 and 8 have the operating plungers 19 and 20 working therein. The plungers 19 and 20 have cross heads 59 and 60 formed integral with the upper ends, these cross heads being guided in suitable guides 61 and 62, which are preferably formed integral with the side frame members 40 and 41. The cross heads 59 and 60 are connected by suitable wrist pins 63 and 64, to connecting rods 26 and 27, respectively. These connecting rods in turn are connected to crank pins 24 and 25, the crank pins being adjustably seated in holes in the crank discs 65 and 66. The holes in the crank discs 65 and 66 are placed at various radial distances from the center of the crank shaft 21 so that the stroke of the pistons or plungers 19 and 20 may be adjusted. These holes are shown at 67 in Fig. 5 in disc 66. A corresponding series of holes is provided in the disc 65, holes at the same radial distance being spaced 180° apart so as to maintain synchronism.

The crank shaft 21 has suitable journal bearings at 68 and 69 at the top of the frames 40 and 41, respectively. A bull gear 70 is splined onto the crank shaft 21 and it is driven by a pinion 71 on the counter shaft 72. The counter shaft 72 has suitable bearings 73 and 74 on the frames 40 and 41 and it has in turn a bull gear 75 keyed thereto, which is driven by the power pinion 77 keyed to the power or drive shaft 78. The power or drive shaft 78 has journal bearings as indicated at 79 in the frame members and said power shaft 78 extends off laterally to make suitable driving connection with an electric motor, gasoline engine or other source of power for driving the jack. Preferably a belt pulley is mounted on the shaft 78 and the same is driven by a belt from an electric motor, gasoline engine or the like.

The bull gear 70 has a valve operating cam 80 adjustably bolted to one side thereof as 110 by means of the bolts or cap screws 81, suitable slots being provided in said cam 80 to permit of angular adjustment of the cam 80 about the shaft 21. The upper end of the thrust rod 29 which operates the discharge valve 28 is provided with a follower in the form of a roller 82 held against the face of the cam 80 as by means of the compression spring 83. The thrust rod 29 is suitably guided in the cross frame members 44 and 45 and the upper end is also guided by a bracket 84, which is attached to the gear cover for the bull wheel 70, which cover for the sake of clearness has been omitted from the 115 drawing.

The cam 80 has a suitable lift or dwell for depressing the push rod 29 at the beginning of the downward stroke of the plunger 20 which downward stroke of the plunger 20 120 125

performs the discharge stroke of the pump in the well.

It will be observed that I have shown the plunger 20 of a diameter slightly larger than the plunger 19. This I have done to make up for the difference in displacement of the two sides of the piston 13 in the cylinder 12, which is caused by the volume of the connecting rod 14.

10 It is not necessary that the displacement of the plungers be made to correspond so accurately to the displacement of the motor piston 13 since I have provided other means for compensating for the difference in displacement required for the two strokes of the pump, but it will be apparent that less displacement is required theoretically to raise the plunger 13 than to depress the same.

15 It can now be seen that by applying power to the drive shaft 78 the counter-shaft 72 is actuated and this in turn drives the crank shaft 21 reciprocating the pistons 19 and 20 to depress the fluid column in one pipe while the fluid column in the other pipe rises and vice versa. Also, upon each stroke of the piston 20 the let-off or discharge valve 28 is opened to permit the discharge of oil into the receiver or reservoir into which it is pumped.

20 As previously explained it is necessary to make provision for releasing the gas which is evolved in either or both columns during normal operation of the device. To this end the plungers 19 and 20 are provided with gas release valves as indicated at 86 and 87 in Fig. 1. These gas release valves and their controlling mechanism are the same for both plungers and hence the description of one of them will suffice for both.

25 Referring now to Figs. 6, 7 and 8, it will be seen that the plunger 20 is drilled longitudinally to provide a bore 91 in which there is disposed a valve operating rod 88 having suitable guiding wings 89 at its upper end and guiding wings at 90 along its central portion. The lower end of the plunger 20 is counterbored and a hardened valve seat member 92 is pressed into place in said counterbore to form a seat for the ball valve 87. A perforated cap member 93 is threaded into the lower end of the plunger member 20 and it contains a spring 94 tending to seat the ball 87 upon the seat member 92. The cap member 93 thus forms a cage for the spring and the valve, but due to the longitudinal 30 perforations therethrough fluid is permitted to pass freely through said cage when the valve 87 is thrust from its seat by rod 88. The longitudinal bore 91 communicates with an outlet passageway 95 at the upper end of the plunger 20, this outlet passageway terminating in a pipe socket into which is threaded the nipple 96. The nipple 96 communicates with an elbow 97 and the elbow 97 in turn is connected to a pipe 98 which 35 has a flexible hose 99 connected thereto, this

hose leading through a valve 100 to a common gas discharge pipe 101 which leads to the top of the reservoir or receiver into which oil is pumped or to any other suitable receiving connection.

70 The plunger 19 likewise has the same construction and employs a similar flexible hose connection 99' leading through a control valve 100' to the same gas discharge pipe 101.

75 The means for operating the valve push rod 88 comprises a cam shaft 103 having a cam 104 thereupon disposed in a recess 105 in the metal of the cross head 60 above the plunger 20, the bore 91 continuing past the passageway 95 into said recess 105 so that the head of the push rod 88 engages the cam member 104, the valve spring 94 being strong enough to raise the valve from its seat and to maintain at other times the push rod 88 in engagement with the cam 104. An anti-friction bushing 106 is threaded in the open end of the pocket or recess 105 to form a bearing for the cam shaft 103. The inner end of the cam shaft 103 has a bearing in the body of the cross head 60. The bearing 80 bushing 106 is counterbored to form a gland pocket for receiving packing 107 held in place by a gland follower 108.

85 The cam shaft 103 bears at its outer end an operating arm 109, said arm bearing at 90 its outer end a roller 110 for the purpose of engaging suitable controlling members or guides, as will be explained in detail later. A helical torsion spring 111 has its outer end connected as by means of the pin 112 to the arm 109 and it has its inner end secured to a light metal bracket 113, this bracket being U-shaped and having its end secured to the sides of the cross head member, as will be apparent from Fig. 8. The cam shaft 103 passes through an opening in said bracket and the helical spring which surrounds the shaft 103 has its inner end secured as by means of the pin 114 to said bracket 113. The spring 111 tends at all times to rotate 95 the crank arm 109 and shaft 103 in a clockwise direction to permit the valve spring 94 to close the valve 87. In all the positions of the valve 87 during the downward stroke it is closed so that pressure may be exerted 100 upon the corresponding liquid column.

105 The hub of the arm 109 is notched as indicated at 115 in Fig. 6, and this notch is adapted to be engaged by the nose 116 of a pawl member 117. This pawl member 117 is 110 mounted on a stud 118 supported on the cross head 60. The rear end of the pawl 117 has a shoulder 119 which is adapted to be engaged by a trip adjustably disposed in the path of the same for tripping the hook 116 out of the notch 115 to permit the spring 113 to turn the cam shaft so that the valve 87 may be closed.

115 The means for rotating the cam shaft and arm 109 so that the nose or hook 116 of the 120

pawl 117 may be engaged will now be described. The guide 62 which is integral with the frame 41 receives the cross head member 60, the guide being open at the outside. Longitudinal frame members 120 and 121 are bolted to the opposite sides of the cross head guide 62 as by means of the bolts 122. These bolts pass through suitable flanges on the frame members 120 and 121 to hold the frame members rigidly to the guide 62. These frame members 120 and 121 have longitudinal grooves 123 and inturned flanges 124 along their outer edges. The flange 124 at the left side of Fig. 6 is continuous throughout the lengths of said side frame member 120, whereas the corresponding flange 124 on the right side of Fig. 6 is cut away throughout the central part of the corresponding frame member 121. A cover plate 126 bears against the inside of the flanges 124 and steel strips rectangular in cross section, shown at 127 and 128 lie within the grooves 123 against the margins of the cover plate 126 and these strips and the margins of the plate 126 are clamped to the inside of the flanges 124 by the cap screws 129. The roller 110 on the arm 109 is adapted to be brought into engagement with said strips 127 and 128, as will be apparent later. The pawl 117 is counter-weighted so that the nose 116 thereof tends at all times to enter the notch 115 when said notch is brought into register. The pawl 117 is tripped out by an adjustable trip member 130. This adjustable trip arm 35 constitutes a pivoted member having a shoulder 131 normally lying in the path of the shoulder 119 on the rear end of the pawl 117. The trip 130 is mounted pivotally on a stud 132 which is secured upon the adjustable trip plate 133, this plate being provided with a series of slots 134, through which project corresponding studs 135, which are secured in the cover plate 126. The outer ends of the studs 135 are provided with clamping nuts so that the plate 133 may be clamped in any desired position against the cover plate 126. It can now be seen that the flange 124 on the right hand side of Fig. 6 is made discontinuous so that the plate 133 may extend 40 out beyond the edge of the guide 121. The pin 132 lies clear of the side frame member 121, but the shoulder thereof, as shown at 131 in Fig. 6, projects through a slot in the side frame member, as can be seen in Fig. 4. A 45 slot is shown in Fig. 4 at 136. By means of the adjustable plate 133 the trip 130 may be disposed at any selective point within limit so as to secure the desired closing of the valve at any point in the stroke of the plunger 20 50 within limits.

The opposite frame member 120 is slotted in a similar manner to permit the pipe 98 to pass therethrough and to be reciprocated with the plunger. Such a slot is indicated 65 at 137 of Fig. 4 for the plunger 19.

A pin 138 is mounted in the adjustable plate 133 for stopping the counter-clockwise motion of the member 130 and a limit pin 139 limits the clockwise rotation of the same when the rear end of the pawl 115 rises and lifts the shoulder 131 of the member 130. 70

Obviously instead of a swinging trip member 130 a sliding member, such as shown at 140 in Fig. 11 may be employed. The sliding member 140 has a tapered face, like a door latch bolt so that the rear end of the pawl 117 may push the member 140 into a recess against a spring 141 which spring projects the member 140 outwardly as soon as it is cleared by the pawl 117. 80

The means for opening the valve at the lower end of the stroke will now be described. A swinging guide arm 142 is pivoted on a shoulder bolt 143 secured to the cover plate 126. The swinging guide 142 is provided with an adjustable weight 144 to cause the guide to swing counter-clockwise so that the end of the same engages the guide strip 128 (see Fig. 6). The weight 144 is in the form of an arm fastened at its inner end by a set screw to a stud 145 which stud passes through a slot in the cover plate 126 and is secured to the guide 142 adjacent the pivot pin 143. 90

Assume that the operating arm 109 for the cam shaft 103 is in the position shown at the top in dotted lines in Fig. 6. As soon as the rear end of the pawl 117 engages the shoulder 131 of the trip member 130 the hooked end of the pawl 117 will be thrown out of the notch 115 in the hub of the arm 109, and the spring 111 thereupon promptly throws the cam 104 to a position permitting the spring 94 to close the valve 87, whereupon the plunger stroke downward is made without the escape of fluid past the valve 87. This valve seats with pressure and therefore remains tight even under extreme pressure. As the spring 111 throws the arm 109 in clockwise direction, as viewed in Fig. 6, the roller 110 engages the guiding strip 128 and follows downwardly along the same as indicated by the arrow 147, (see Fig. 6). The roller in its descent pushes the guide arm 142 out of the way, as shown in the dash and dot line on Fig. 6. In its downward stroke, the roller 110 passes below the nose of the guiding arm 142 and immediately upon its upward stroke, as indicated by the arrow 148, is compelled to pass to the left of the guide arm 142 whereby the spring 111 is placed under tension, and at the same time the cam 104 is operated to depress the push rod 88 for opening the valve 87. The hook 116 of the pawl 117 drops into the notch 115 holding the arm 109 110 and its connected parts in such position that the valve 87 is open during the complete upward stroke of the plunger 20. Thus, during the part of the operation when the corresponding liquid column is not under pres- 120

125

130

sure an escape is provided for fluid, particularly gas, which may rise in the corresponding column to escape out through the lateral passageway 95, pipes 96, 98, flexible hose 99 and discharge pipe 101.

Whereas the evolution of gas occurs mainly in the discharge liquid column, I find it advisable to provide an escape for gas or other fluid from the plunger which operates the inner liquid column, since the continued agitation of the liquid by reciprocation of the column tends to evolve gas even though the same liquid is used over and over in the inner column.

15 The above described valve 87 and its operating mechanism is also useful for controlling the displacement of the corresponding plungers.

The displacement of the plungers is preferably made greater than the corresponding actual displacement of the motor piston in the pump and the useful displacement may be controlled by suitable setting of the adjustable trip whereby a part of the actual displacement may be released and only the selected part utilized.

This feature of controlling the effective displacement of the jack plunger, of plungers, is of importance, particularly in connection with the continued pumping of oil from a well. The capacity of the pump 1 at a given number of strokes per minute may be considerably in excess of the production of the well, that is, the rate at which liquid flows from the well to the pump. It is desirable to operate the pump in such a manner that it will pump the liquid as rapidly as it flows into the well, but not any faster. If the pump had, for example, a complete stroke of ten foot traverse, it might be desirable to cut the stroke down to say six feet or four feet or three feet, depending upon the rate of production of oil in the well. By suitably setting the point of closing of the stroke control valve, the jack plunger may be caused to displace into the column only sufficient liquid to make the shorter stroke of the pump desired to meet the rate of production in the well. In this manner, the rate of pumping may be coordinated with the rate of production of oil in the well merely by controlling the point of closure of the stroke control valve or valves.

Variation of the actual displacement of the plungers may be secured by adjustment of the crank pin on the crank disc as previously explained.

The head mechanism may be used with the pump shown in my prior copending application, as indicated in Fig. 1, or it may be employed with modified forms of the same, as illustrated diagrammatically in Figs. 2 and 3. For example, in Fig. 2 a differential motor piston is employed, this being particularly useful in a well which has a tendency to

gas. The inner pipe 6 is connected to the top of a small motor cylinder 150 which forms a direct continuation of a larger motor cylinder 151. Since the space between the pistons is not subjected to the actuating pressures these cylinders in effect constitute a single double acting cylinder and the piston structure constitutes a single double acting piston.

Suitable pistons 152 and 153 are connected by a rod 154 and are also connected to the pump plunger 155 by a rod 156. A longitudinal passageway 157 extends from the space between the pistons 152 and 153 through the pump piston 155 to the space below the latter, said passageway being controlled by a check valve 158 to permit evacuation of the space between the pistons 152 and 153, said passageway also communicating with the space above the piston 155 in cylinder 10 to permit evacuation of any fluid from said latter space at the same time.

By this arrangement the depression of the liquid column in the pipe 6 acts upon the piston 152 to make the discharge stroke of the pump piston 155. The area of the piston 153 is substantially greater than the area of the piston 152, so that under equal heads within the pipes 3 and 6 there is a tendency for the greater force exerted on the piston 153 to raise the connected pistons without additional pressure being imposed by the corresponding pump plunger 19. Under these conditions I may dispense with the plunger 19 and employ only the plunger 20 connected to the pipe 6, depending solely upon the difference in area to make the suction stroke. In that event, the column in the pipe 6 could be maintained full of oil by placing a slight head of the same above the valve 87 and synchronism between the jack and pump maintained by the transfer valve 35.

I have shown in Fig. 3 a modified form of the pump shown in Fig. 1 in which the area of the piston 13 is greater than the area of the piston 15 and the upper end of the cylinder 10 is open to the interior of the discharge pipe 3, so that the suction stroke is made by the difference in force resulting from the different areas of the pistons 13 and 15 upon the application of pressure to the discharge line.

In the jack which I have above described the gas release valves are located directly in the plungers, but it will be apparent to those skilled in the art that while this is the preferred method of construction it is not essential to the fundamental features of my invention. The provision of gas release valves at suitable points in the columns operated synchronously with the stroke producing mechanism to permit the escape of gas when the pressure on the corresponding column is released is the desired structure and action.

I do not intend to be limited to the details shown and described.

I claim:—

1. In a system of the class described, a cylinder, a piston therefor, means for reciprocating the piston at a predetermined constant rate, a let-off valve communicating directly with the cylinder for releasing excessive fluid from the cylinder and automatic means for opening said valve during a pre-determined portion of the stroke of said piston. 70
- 10 2. In a system of the class described, a cylinder, a piston therefor, means for reciprocating the piston at a predetermined constant rate, a let-off valve carried by the piston for releasing excessive fluid from the cylinder and automatic means for opening said valve during a pre-determined portion of the stroke of said piston. 75
- 15 3. In combination a vertical cylinder, a single acting plunger entering the top of the cylinder, said plunger having a passageway therethrough, a let-off valve for said passageway for releasing gas from the cylinder, and means for periodically opening and closing said valve. 80
- 20 25 4. In a device of the class described, a substantially vertical cylinder, a plunger therefor entering the upper end of the same, a cross head for the plunger, a guide for the cross head, said plunger having a passageway extending through the same to a point adjacent the cross head, a check valve controlling said passageway, a thrust rod for opening said check valve, a cam for operating said thrust rod, said cam being carried by the plunger, and means carried by the guide for operating said cam. 90
- 30 45 5. In combination, a cylinder, a plunger therefor, a cross head for the plunger, a guide for the cross head, said plunger having a passageway therethrough, a valve controlling said passageway, and means within the plunger for holding said valve open during a pre-determined part of the stroke of said plunger, whereby the plunger idles during that part of the stroke. 105
- 50 55 6. In combination, a cylinder, a plunger therefor, a let-off valve for releasing fluid from the cylinder during a pre-determined portion of the stroke of the plunger, and means carried by the plunger for operating said let-off valve. 110
- 60 65 7. In combination, a cylinder, a plunger for the cylinder, a let-off valve for the cylinder for releasing fluid from the cylinder during a pre-determined portion of the stroke of the plunger, means tending at all times to close said valve, detent means for restraining said closing means, said detent means being carried by the plunger, and a relatively stationary trip member for releasing said detent means. 115
- 70 75 8. In combination, a cylinder, a plunger therefor, a release valve operable during a pre-determined portion of the stroke of the plunger to discharge fluid from the cylinder, 120
- 80 85 9. In combination, a liquid column adapted to be reciprocated, a motor cylinder communicating with one end of the column and having a piston adapted to be moved by a movement of said column, a second cylinder communicating with the opposite end of said column, a piston therefor, and means operable on each return stroke of the latter piston for releasing gas at the top of the column. 125
- 90 95 10. In combination, a liquid column adapted to be reciprocated, a motor cylinder communicating with one end of the column, and having a piston adapted to be moved by movement of said column, a second cylinder communicating with opposite end of said column, a piston therefor, means to move said second piston through a fixed stroke of greater displacement than the displacement of said motor piston, and means operable upon each compression stroke of the second piston to release fluid from the latter cylinder until the displacement of the remainder of the fixed stroke equals the displacement of the motor piston. 130
- 100 105 11. In combination, a pair of liquid columns adapted to be reciprocated, a motor member adapted to be reciprocated by said columns, a pump element actuated by said motor member, said pump element discharging liquid into one of said columns, a pulsator for reciprocating said columns, a synchronously operated discharge valve for discharging from said one column the liquid pumped there into at each stroke, and a gas release valve operated during the operation of the discharge valve for releasing gas from said one column of liquid. 135
- 110 115 12. In combination, a pair of liquid columns one of which is adapted to be put under pressure while pressure on the other is released and vice versa, said columns being concentric to one another at the bottom, a motor member reciprocated by said columns, said motor member extending longitudinally of said columns at the bottom of one of said columns, a pulsator for applying and releasing pressure on said columns, and a cross connection between said columns, said cross connection containing a loaded check valve. 140
- 120 125 13. In combination, a conduit containing a column of liquid, a pulsator cylinder connected to one end of the conduit, a motor cylinder connected with the other end of the conduit, pistons for said cylinders, the pulsator piston having a stroke providing a greater displacement than the stroke of the motor piston, a let-off valve synchronously operated with the pulsator piston for releas-

- ing fluid from the pulsator cylinder during a pre-determined portion of the stroke of the pulsator piston, and a loaded release valve communicating with the conduit.
14. In combination, a pair of liquid containing conduits, pulsator cylinders communicating with the upper ends of the conduits, the lower end of said conduits being coaxial, a motor member separating the lower ends of the conduits and being reciprocable by reciprocation of the liquid columns in the conduits, means controlled by the motor element for imparting an upward drift to the liquid in one of said columns, and cross connections between the conduits for synchronizing the motion of the motor member with the pulsator pistons, said connections including loaded check valves.
15. In combination, a pair of conduits, a pulsator communicating with the upper ends of the conduits, a motor member between the lower ends of the conduits, said conduits being adapted to be filled with liquid columns, a pump element operated by the motor member to discharge liquid into one of the conduits, a valve operated synchronously with the pulsator for drawing off from said one column the liquid discharged thereinto by the pump, and cross connections between the conduits for synchronizing the pulsator with the motor member, said cross connections including loaded check valves.
16. In combination, a conduit adapted to contain a column of liquid, a pulsator connected to the upper end of the conduit, a motor cylinder connected to the lower end of the conduit, a piston therefor, said pulsator piston having a fixed stroke, said motor piston having a fixed stroke of less displacement than that of the pulsator piston, and a let-off valve automatically opened during a part of the stroke of the pulsator piston, for letting off gases and for securing the proper liquid displacement of the pulsator piston required to make a substantially complete stroke of the motor piston.
17. In combination, a pair of conduits adapted to contain liquid columns, a pulsator connected to the tops of said columns, and a motor member adapted to be reciprocated by said liquid columns and disposed between the lower ends of the same, means controlled by said motor element for imparting an upward drift to the liquid in one of the columns, and means for synchronizing the motor member with the pulsator to secure substantially full stroke of the motor member each way.
18. In combination, a pair of conduits adapted to contain liquid columns, a pulsator connected to the tops of said columns, a motor member adapted to be reciprocated by said columns, and disposed between the lower ends of the same, the lower ends being coaxial, means operable upon lack of synchronism of the pulsator and motor member for transferring liquid from one column to the other, and means controlled by said motor element for imparting an upward drift to one of said columns.
19. In an apparatus wherein pumping means at the bottom of a well is actuated by two reciprocating columns of liquid to pump liquid by imparting an upward drift to one of said columns, the combination of means for reciprocating said columns, discharge means controlling the discharge of liquid from the upwardly drifting column, and additional means for controlling the discharge of gases formed in said last mentioned column.
20. In an apparatus wherein pumping means at the bottom of a well is actuated by two reciprocating columns of liquid to pump liquid by imparting an upward drift to one of said columns, the combination of means for reciprocating said columns, discharge means controlling the discharge of liquid from the upwardly drifting column, and additional means effective only during a predetermined portion of the operating cycle of the columns for discharging gases formed in said last mentioned column.
21. In an apparatus wherein pumping means at the bottom of a well is actuated by two reciprocating columns of liquid to pump liquid by imparting an upward drift to one of said columns, the combination of means for alternately applying pressure to said columns for reciprocating the same, and gas release valves operated synchronously with said last means for permitting the escape of gas from one of said columns when the pressure upon that column is released.
22. In an apparatus wherein pumping means at the bottom of a well is actuated by two reciprocating columns of liquid to pump liquid by imparting an upward drift to at least one of said columns, the combination of piston means for reciprocating said columns, discharge means controlling the discharge of liquid from the upwardly drifting column and valve means carried by the piston means for permitting the discharge of gases from at least one of said columns during a portion of each stroke of the piston.
23. In combination, a cylinder, a piston within the cylinder, means for reciprocating the piston, a column of liquid terminating at the cylinder, liquid discharge means and gas discharge means for said column, valves for each of said discharge means, and means for opening and closing both of said valves in synchronism with the piston.
24. In combination in a hydraulic jack, a pair of cylinders, pistons for said cylinders, means for operating said pistons in synchronism but in different phase, valve means controlling the effective length of the working stroke of the pistons, and means for ad-

justing individually the point of operation of said valve means for the respective pistons.

25. In a hydraulic jack, a pair of single acting cylinders, plungers therefor, means for actuating said plungers to make alternate pressure strokes, valve means for permitting escape of the contents of the respective cylinders during a predetermined fractional part of the strokes of the respective plungers thereby controlling the effective length of the stroke of the plungers, and means for individually adjusting the operation of one of said valve means independently of the adjustment of the other.

15 26. In a hydraulic jack, a cylinder, a plunger therefor, a crank for operating said plunger, a valve, means to hold said valve open during the initial part of the working stroke of the plunger to permit escape of the 20 contents of said cylinder, thereby controlling the effective length of the working stroke of the plunger, and means for closing said valve at a predetermined point in the working stroke of said plunger, the major portion of 25 the working stroke being subsequent to the closing of the valve.

27. In combination, a cylinder, a piston therefor, means to reciprocate the piston in the cylinder, there being an escape passageway for permitting escape of the contents of 30 the cylinder during a part of the compression stroke of the cylinder, a valve for said passageway for controlling the effective length of the stroke, said valve seating with 35 pressure, a spring for applying said valve to its seat, and means comprising a cam track and a cooperating roller governing the opening of said valve, said roller and cam track being relatively movable with respect to each 40 other in synchronism with the movement of the piston.

28. In combination, a liquid column adapted to be reciprocated, a motor cylinder communicating with one end of the column and having a piston adapted to be moved by 45 a movement of said column, a second cylinder communicating with the opposite end of said column, a piston therefor, means for making a fixed stroke of the latter piston, and a 50 synchronously operated valve for permitting escape of a part of the liquid between said two pistons during a predetermined part of the pressure stroke of said latter piston.

29. In combination, a liquid column adapted to be reciprocated, a motor cylinder 55 communicating with one end of the column and having a piston adapted to be moved by a movement of said column, a second cylinder communicating with the opposite end of 60 said column, a piston therefor, means for making a fixed stroke of the latter piston, a synchronously operated valve for permitting escape of a part of the liquid between 65 said two pistons during a predetermined part of the pressure stroke of said latter piston, and

means for adapting the displacement of said second piston in its cylinder to the displacement of the first piston comprising a stroke controlled valve and means operating synchronously with the second piston for 70 controlling the operation of said valve.

30. In a deep well pumping apparatus wherein liquid is pumped by reciprocating two columns of liquid and imparting an upward drift to one of said columns, means for intermittently applying pressure to one of said columns, valve means associated with each of said columns for discharging gases that may rise in the respective columns, means controlled by the first named means 80 for operating said valve means, and means for adjusting the point of operation of one of said valve means.

31. In a deep well pumping apparatus wherein liquid is pumped by reciprocating two columns of liquid and imparting an upward drift to one column, means for intermittently applying pressure to one of the columns, valve means associated with each of the columns for discharging gases that 90 may rise in the respective columns, means controlled by the first named means for operating said valve means, and means for independently adjusting the point of operation of each of said valve means.

32. In a deep well pumping apparatus wherein liquid is pumped by reciprocating two columns of liquid and imparting an upward drift to one of said columns, means for intermittently applying pressure to one of said columns, means for discharging liquid from the upwardly drifting column, and means independent of said last named means for discharging gases that may rise in the upwardly drifting column.

33. In combination, a fluid pressure cylinder, a piston therein, means for reciprocating the piston to perform work on the fluid in the cylinder, said piston having an opening therein to permit the free escape of the fluid therethrough upon the reciprocation of the piston, means for closing said opening during the working stroke of the piston and adjustable means for controlling the point of closure of said closing means whereby the effective length of the working stroke of the piston may be varied.

34. In combination, a cylinder, a piston therein, said piston having a fixed stroke in the cylinder, and means for controlling the length of the effective portion of the stroke, said means including a discharge passageway permitting the escape of fluid from the cylinder past the piston upon the reciprocation of the piston, valve means for closing and opening the passageway, and means controlled in synchronism with the piston for controlling the valve, said last means including means for adjusting the point of operation of said valve means.

35. In combination, a pair of fluid columns, a pump having a motor piston interposed between the lower ends of said columns, a hydraulic jack having a cylinder connected to one of said columns and having a piston reciprocable therein and a valve operated synchronously with said piston for permitting the escape of any predetermined part of the liquid displaced by said jack piston for obtaining the desired travel of said motor piston.

In witness whereof, I hereunto subscribe my name this 17th day of September, 1927.
